UNITED STATES PATENT OFFICE.

HENRY STEENBOCK, OF NEW YORK, N. Y.

ZITHER.

SPECIFICATION forming part of Letters Patent No. 678,525, dated July 16, 1901.

Application filed April 25, 1901. Serial No. 57,361. (No model.)

To all whom it may concern:

Be it known that I, HENRY STEENBOCK, a citizen of the United States, and a resident of New York city, county and State of New York, 5 have invented certain new and useful Improvements in Zithers, of which the following is a specification.

This invention relates to an improved zither of the class in which the strings are sounded 10 by means of hammers actuated by keys.

By my invention the strength and compactness of the instrument are increased and its construction simplified.

In the accompanying drawings, Figure 1 is 15 a plan of my improved zither. Fig. 2 is a vertical longitudinal section on line 2 2, Fig. 1. Fig. 3 is a plan, on a reduced scale, of the body of the zither; and Fig 4, a cross-section on line 4 4, Fig. 3.

20 The letter *a* represents the resonating-chamber or main body of a zither having the usual sounding-board *a'*, while openings *a²* *a³* are provided in the top and also in the front of the chamber. To the sides of the body *a* are 25 secured the forwardly-projecting arms *b*, to the ends of which is in turn secured the bridge *c*. This bridge is placed parallel to the front of the zither-body, but at a distance therefrom, so as to leave an intermediate 30 opening *d*, traversed by a brace or braces *b'*. The strings *e*, arranged in the usual manner, extend from the bridge *c* over the opening *d* and over the sounding-board *a'* to the tuning-pins *f*.

35 *g g* represent the keys, projecting upwardly from levers *g'*, that turn on a common pivot *g³* and have rear cam - surfaces *g²*. These cam-surfaces engage reverse cam-surfaces *h'*, formed on the front ends of the hammers *h*, 40 which turn on a common pivot *h³* and project underneath the bridge *c* and into the open space *d*. Thus when the keys are depressed the hammers will be thrown upwardly in the opening *d* between body *a* and bridge *c*, so as to strike the lower sides of the strings stretched across such opening. When 45 the keys are released, the levers and hammers will fall back into their normal position by gravity. By causing the hammers to vibrate 50 within the opening *d* and to strike the strings

from the bottom the height of the instrument need not be increased for permitting the movement of the hammers, and thus great compactness is obtained.

The damper *i* is made in the form of a cushioned bar extending underneath all the strings. This damper is also accommodated within the opening *d* and is operated by a hand-lever *i'*, secured to a pivot-bar *i²*, that is connected to damper *i* by arms *i³*. If the lever *i'* is depressed, the damper is raised against the lower sides of the strings, while if the lever is released the damper is lowered off the strings by springs *i⁴*.

It will be seen that in my improved zither 65 great strength and compactness are obtained and that all the operating parts are thoroughly inclosed and protected. The front openings *a³* also contribute considerably to increase the volume of tone. 70

What I claim is—

1. In a zither, the combination of a resonating-chamber with a bridge placed at a distance therefrom, strings spanning the opening between bridge and resonating-chamber, 75 and hammers adapted to oscillate within said opening and to engage the lower sides of the strings, substantially as specified.

2. In a zither, the combination of a resonating-chamber with a bridge, arms for securing the bridge to the resonating-chamber at a distance therefrom, strings spanning the opening between the bridge and resonating-chamber, and hammers extending beneath the bridge and adapted to oscillate within said 85 opening, substantially as specified.

3. In a zither, the combination of a resonating-chamber with a bridge, arms for securing the bridge to the resonating-chamber at a distance therefrom, strings spanning the opening between the bridge and resonating-chamber, key-levers having cam-shaped ends, and hammers having cam-shaped ends and adapted to oscillate within the opening between the resonating-chamber and the bridge, 90 substantially as specified.

4. In a zither, the combination of a resonating-chamber having a perforated top and a perforated front, with a bridge, arms for securing the bridge to the resonating-chamber, 95

ber at a distance therefrom, strings spanning the opening between the bridge and resonating-chamber, and with hammers and a damper that are adapted to oscillate within said opening and to engage the lower sides of the strings, substantially as specified.

Signed by me at New York city, county and

State of New York, this 24th day of April, 1901.

HENRY STEENBOCK.
